INTERNAL COMBUSTION ENGINE STARTING MECHANISM

Filed Sept. 11, 1929

VICTOR F. ZAHODIAKIN
INVENTOR.

Leo A. Parker
BY
ATTORNEY.

UNITED STATES PATENT OFFICE

VICTOR F. ZAHODIAKIN, OF CINCINNATI, OHIO

INTERNAL COMBUSTION ENGINE STARTING MECHANISM

Application filed September 11, 1929. Serial No. 391,797.

The invention relates to means for starting or rotating internal combustion engines.

The objects of the invention are to provide a simple, efficient and practical means 5 adapted to transmit power from a starting motor to an internal combustion engine fly wheel, or other suitable rotatable part; to provide means whereby the power transmitting mechanism is adapted to render satisfying 10 factory service and long usage with minimum expense for repairs and replacements of parts; to provide means adapted to transmit power from said starting motor to said fly wheel by frictional engagement of moving parts thereby eliminating the risk of stripping gear teeth and providing a noiseless device of this character; to provide means whereby said frictionally engaged parts are adapted to eliminate lost motion 15 thereby transmitting said power with minimum loss resulting from wasted motion; to provide means whereby long usage of said device will not result in unimproved operation of the mechanism; and to provide 20 means whereby the frictionally engaged parts are automatically adjusted with respect to each other.

The invention consists in the arrangement of the parts, combination of the elements, and in the details of the construction, 30 as hereinafter claimed.

In the drawings:

Fig. 1 is a rear end elevation of an internal combustion engine showing the invention incorporated therewith;

Fig. 2 is a section taken on a line corresponding to 2-2 in Fig. 1;

Fig. 3 is a section taken on a line corresponding to 3-3 in Fig. 1;

40 In the preferred construction of the invention I provide the usual starting motor 1 having its casing 2 secured, by the bolt 3, to the casing 4 having its lower edge 5 bolted to the lower crank case casing 6 which also surrounds the usual fly wheel 7 fixed to the rear end of the usual crank shaft 8 of the internal combustion engine 9.

45 The shaft 10, of the motor 1, has a plurality of spaced apart V-shape, or tapered 50 grooves 11, formed circumferentially there-

of, the outer end 12 of the shaft 10 being rotatably mounted in the casing 4.

55 Integrally formed in the outer circumferential surface 13, of the fly wheel 7, are the spaced apart V-shape, or tapered grooves 14, aligned with the respective grooves 11.

60 Intermediate the shaft 10 and the fly wheel 7 is the idler wheel 15 rotatably mounted on the shaft 16 having its ends 17 received through the holes 18, in the case 19, to which are threaded the nuts 20. Around the shaft 16 is the bushing 21 upon which is mounted the plurality of wheels 22 having the members 23 integral with their hubs 24. The members 23 are adapted to closely fit 65 into the grooves 11 and 14, respectively, into the shaft 10 and the fly wheel 7.

70 Integral with the casing 19 is the arm 25 slidably mounted in the hole 26 in the casing 4.

75 Slidable upon the outer end of the arm 25 is the cup 26 having the coiled spring 27 therein adapted to force the cup outwardly from the arm.

80 Through the arm 25 is the pin 28 against which the end 29 of the coiled spring 30 presses, having its other end 31 engaging the casing 4, whereby the casing 19 is forced inwardly of the casing 4 to the limit of contacting of the pin 32, received through the 85 arm 25, with the casing 4.

85 Slidably mounted in the frame 33, suitably fixed to the casing 4, is the rod 34 having the projection 35 adapted to engage the cup 26; when the rod is forced inwardly as shown in Fig. 3. The spring 36 received around the rod 34 and engaging the frame 33 and the head 37, of the rod, normally forces the rod outwardly and disengages the projection from the cup 26.

90 Fixed to the support 38, fixed to the casing 4, is the switch 39 having the conductors 40 and 41 respectively, leading to the terminal 42, of the battery 43 and the starting motor 1. The other terminal 44 of the battery is grounded to the casing 4 of the engine 9, as by the conductor 45.

95 The end 46, of the rod 34 is adapted to engage the switch 39, after the rod is forced inwardly with the projection 35 in engage-

ment with the cup 26, whereby the circuit from the battery 43 to the starting motor is closed thereby causing the shaft 10 to rotate.

6 Engagement of the projection 35 with the cup 26 forces the tapered portions 23 of the wheels 22 in the grooves 11 and 14 of the shaft 10 and the fly wheel 13 whereby the fly wheel is rotated imparting rotary movement to the crank shaft 8.

10 The spring 37 automatically forces the rod 34 outwardly disengaging the projection 35 from the cup and the end 46 from the switch 39 when manual inward pressure 15 is released from the head 37 of the rod.

The head 37 may be projected from the floor board, or elsewhere, when the device is utilized on an automobile.

An advantage of the invention is that 20 when power is transmitted from the starting motor to the fly wheel the machine is practically noiseless.

Moreover, the power is transmitted, irrespective of the relative speeds of the starting motor and the fly wheel without likelihood of damaging the mechanism.

Therefore, I have invented a practical and highly desirable device for the purposes intended, and while I believe that the form of 30 the invention illustrated in the drawings and referred to in the above description is the preferred embodiment, and is efficient and practicable, yet I realize that the conditions under which the device may be operated will necessarily vary, for which reason I desire to emphasize the fact that changes in the details of the construction may be resorted to, when required, without sacrificing any of the advantages of the invention 35 as defined in the claims.

In other words, it is understood that changes and modifications in the embodiment of the invention, such as its size, the materials used and the like the shape of the 45 V-shape members and grooves as disclosed herein, can be made within the scope of what is claimed without departing from the spirit of the invention, as other expedients may readily suggest themselves to persons 50 familiar in the art to which the invention appertains.

What I claim as new and desire to secure by Letters Patent is:

1. Means for rotating the crank shaft of 55 an internal combustion engine comprising a rotatable power input member having a tapered groove therein, a rotatable power output member having a taper groove therein and operatively connected with said crank 60 shaft, rotatable means intermediate said input and output members and having tapered means, means to rotate said input member and manually operative means to move said means having tapered means in contact with 65 said input member and said output member

with said tapered means in said grooves, whereby power is transmitted from said input member to said output member, said manual operative means comprising a rod slidably mounted in the casing of said engine and having a projection thereon, an arm connecting with said means having tapered means, said arm being slidably mounted adjacent said engine, a cap on the end of said arm, resilient means intermediate 70 said cap and said arm whereby movement of said rod with said projection and contact with said cap forces said last mentioned tapered means in said grooves.

2. Means for rotating the crank shaft of 80 an internal combustion engine comprising a rotatable power input member having a V-shape groove therein, a rotatable power output member having a V-shape groove therein and operatively connected with said crank 85 shaft, rotatable means having a V-shape member, means to rotate said input member and manually operative means to move said means having a V-shape member in contact with said input member and said output 90 member, with said V-shape member in said grooves, whereby power is transmitted from said input member to said output member, said manual operative means comprising a rod slidably mounted in the casing of said 95 engine and having a projection thereon, an arm connecting with said means having a V-shape member, said arm being slidably mounted adjacent said engine, a cap on the end of said arm, resilient means intermediate 100 said cap and said arm whereby movement of said rod with said projection and contact with said cap forces said last mentioned V-shape member in said grooves.
